UNITED STATES PATENT OFFICE.

JOHN H. KNAPP, OF BLACK RIVER, NEW YORK.

SHADE-BRACKET.

1,233,248.

Specification of Letters Patent. Patented July 10, 1917.

Application filed November 24, 1916. Serial No. 133,194.

To all whom it may concern:

Be it known that I, JOHN H. KNAPP, a citizen of the United States, residing at Black River, in the county of Jefferson and State of New York, have invented certain new and useful Improvements in Shade-Brackets; and I do hereby declare the following to be a full, clear, and exact description of the invention, such as will enable others skilled in the art to which it appertains to make and use the same.

This invention relates to improvements in shade brackets.

The object of this invention is to provide a shade bracket which may be quickly and readily clamped upon a window frame without marring the woodwork or the use of bolts, brackets or the like and one that can be readily placed in position and removed when it is desired to clean the window upon which it is fitted.

A further object of this invention is to provide a shade bracket which is so constructed as to compensate for various widths of window frames so that the same may be readily applied to window frames of various sizes and the curtain shade placed in position.

A still further object of this invention is to provide a window shade bracket of this character which will be simple, practical and comparatively inexpensive in construction and one that can be manufactured and sold at a comparatively small cost.

With these and other objects in view the invention consists in the novel combination and arrangement of parts hereinafter more fully described and set forth in the claim hereto appended.

40 In the drawings:

Figure 1 is a perspective view of my improved shade bracket made in accordance with this invention,

Fig. 2 is a horizontal sectional view of the same,

Fig. 3 is a perspective view of a slightly modified form of my improved invention.

Like numerals of reference designate corresponding parts in all the figures of the drawing.

Referring to Figs. 1 and 2 of the drawing, wherein there is shown the preferred form of my window shade bracket which comprises in its construction a pair of clamping members designated 1 and 2, the clamping members are constructed of flat sheet metal

and comprise rectangular body portions 3 and 4, which body portions have one end bent at right angles thereto as at 6, the extreme end of the right angularly extending portion bent outwardly as at 7 to provide curtain roller supporting members.

The curtain pole supporting members are provided intermediate their ends with openings 8 which are adapted to receive the telescoping bar 9 therein, the ends of the telescoping bar 9 are rigidly connected in the openings 8 of the portions 7 of the clamping members 1 and 2. A coil spring 10 surrounds the telescoping member 9 and has its ends secured thereto as clearly shown at 11. The spring permits the clamping members to be spread relatively to one another to fit in the frames of various sizes. A pair of extensions 12 are pivotally connected at 13 one end as at 14 and diverge outwardly to present an inverted V-shaped member which has its extreme ends bent angularly as at 15, which angularly bent ends are pivotally secured to the outer surfaces of the portion 7 of the clamping members 1 and 2 as clearly shown in Fig. 1 of the drawing.

A curtain pole supporting member comprises a shank 15 having one end curved upwardly as at 16 which is pivotally connected to the pivoted ends of the member 12 intermediate the ends of the shank 15, the free ends of the shank 15 is provided with a rectangular portion 17 which is adapted to engage the upper surface of a window frame and thus prevent the clamping members 1 and 2 from moving downwardly when clamped thereon.

The inner clamping member 2 is provided with pintle receiving opening 18 which is adapted to receive the pintle of a curtain shade roller therein thus permitting the same to be positioned transversely across the window sash when the device is in use.

When it is desired to use the preferred form of the invention, the clamps 1 and 2 are spread outwardly thus the device is fitted to a window frame on opposite sides of the window sash and the curtain shade roller is arranged therein and it can be readily seen that the device is readily adjustable to various size window frames and is held against downward movement by the member 17 engaging the upper surface of the window frame.

Referring to Fig. 3 of the drawing, wherein is shown a modified form of the inven-

- tion which comprises in its construction a pair of clamp members 18 and 19 which are identical with the members 1 and 2 having the inwardly extending right angled extensions 20 which have the right angular extending portions 21 which portions are parallel with the members 18 and 19, a telescoping bar 22 is connected by each of its ends to the members 21 and is surrounded by a coil spring 23 which permits the clamp members 18 and 19 to be readily spread for fitting various size window frames which window frame is designated A in the drawings.
- 15 One of the clamp members in the modified form of the invention has an upwardly extending arm 24 secured by its lower end and formed integrally with the member 18 as at 25 and has a rectangular portion formed on its upper end and designated 26 which rectangular portion is arranged at right angles to the members 24 and is adapted to engage the upper surface of the window frame to prevent downward movement 20 of the clamp members and also support the clamp members in their position.
- 25 The inner member 19 is provided with an opening 27 which is adapted to receive a

pintle of a curtain shade roller therein for supporting the same transversely across a 30 window sash.

What is claimed is:

A window shade bracket comprising a pair of clamps including rectangular bodies having one of their edges bent at right angles thereto, the edges of the right angularly extending portions bent outwardly and arranged parallel with the body, a telescoping bar having its outer ends connected to the outwardly extending portions, a coil spring 40 surrounding said bar to normally urge the body portions toward one another for clamping action on a window frame, and an inverted V-shaped extension having the extreme ends of its legs connected to each of 45 the outwardly extending portions and a curtain pole supporting member pivotally secured to the apex of the inverted V-shaped member.

In testimony whereof I affix my signature 50 in presence of two witnesses.

JOHN H. KNAPP.
